UNITED STATES PATENT OFFICE.

PETER B. BIRD, OF NEW YORK, AND CHARLES A. BIRD, OF MOUNT VERNON, NEW YORK.

BLOW-OFF COCK.

1,359,785.

Specification of Letters Patent. Patented Nov. 23, 1920.

Application filed January 26, 1917. Serial No. 144,609.

To all whom it may concern:

Be it known that we, PETER B. BIRD and CHARLES A. BIRD, citizens of the United States of America, residing at borough of 5 Kings, city, county, and State of New York, and Mount Vernon, county of Westchester, State of New York, respectively, have invented certain new and useful Improvements in Blow-Off Cocks, of which the following is a specification.

The invention relates to improvements in blow-off cocks and particularly for locomotive and steam boiler use of ranges of relatively high steam pressures.

An object of the invention is to provide a blow-off valve which is held in closing position automatically by the pressure of the boiler. A further object of the invention is to provide a movable valve member which is 15 self-locating or self-positioning. A further object of the invention is to provide a blow-off cock embodying a valve casing which is substantially free from obstruction between its interior end and its discharge opening, 20 a lever for moving the movable member to open position and means for mounting the lever relative to the valve casing and the valve stem and for enabling the lever to be disconnected from the valve casing and to 25 rotate the movable valve member for grinding the same and the valve seat.

More particularly, the preferred form of the invention comprises a valve casing communicating directly with the shell or casing 35 of the boiler, a movable valve member extending through said casing and within the interior of said shell or boiler casing and provided with a valve seat disposed within said valve casing and immediately proximate to the interior of said shell or boiler casing. Such movable valve member is constructed to be automatically closed by the pressure within the shell or boiler casing. Means are also provided for effecting the 40 opening of the valve against the pressure of the steam, the said means comprising a lever pivoted on said valve casing and secured to the valve stem passing through said valve casing.

Further features and objects of the invention will be more fully understood from the following description and accompanying drawings in which—

Figure 1 shows a preferred embodiment

of the invention in side elevation with the 55 lower part of the valve casing and adjacent portion of the boiler casing in central section; and

Fig. 2 is a sectional elevation of a modification.

Referring to Fig. 1, the valve casing 1 comprises the inlet portion 2, the outlet portion 3 and the intermediate curved portion 4. Said inlet portion 2 may be provided with the threaded portion 5 adapted 60 to be tapped into a suitable opening in a side of the boiler casing 6. The outlet casing portion 3 may be provided with the threaded portion 7 adapted to be connected to the piping 8, hose or the like, for direct- 65 ing the discharge to any desired location.

The movable valve member comprises the conical effective valve portion 9 provided with the packing ring 10 disposed along the conical surface of the same and constructed 70 to form a sealing fit with the valve seat 11 when the valve 9 is in closed position. The valve seat 11 is preferably formed at the immediate point of communication of the valve casing 1 with the interior of the 75 boiler 6.

The stem 12 of the movable valve member extends outwardly through the casing 1 and emerges through the adjustable bushing 13. The means for opening the valve is shown as 80 a lever 14 pivotally mounted on the lug 15 and pivotally connected to said valve stem 12 by means of the bolt or pin 16 and slot 17.

The angular flange 18 is provided for positioning or removing the valve casing 1 85 by means of a wrench.

The operation of the aforesaid blow-off valve will be largely understood from the above description together with the following. An essential feature of the valve is the 90 automatic closing of the same by the pressure of the steam or other medium within the boiler 6. It will be noted that the construction affords a superior sealing between the valve and casing by reason of the conical construction of the sealing members. Such construction avoids the formation of any pockets or projecting surfaces susceptible 95 of being incrusted with scale and similar substances. Upon operation of the lever 14, 100 the valve will be forced open and scale, mud and other foreign material will be effectively forced by the pressure of the steam 105

through the valve casing 1 and thereby into the atmosphere or through the discharge piping 8.

The aforesaid form of the invention is simple in construction and in assembling or disassembling. It will be noted that in the event of uneven wearing of the valve seat and seating portion of the movable valve member, the lever 14 is disconnected 10 from its lug 15 by removing the bolt 19, and upon turning the movable valve member through an arc of say one hundred and eighty degrees, the valve seat and seating portion of the valve will be automatically 15 re-ground under pressure of the boiler steam.

It will also be noted that by reason of the conical construction of the effective valve portion, the movable valve member is 20 self-locating, and self-positioning, without the use of any supplemental locating or guiding means.

Even in the event of the valve casing or a portion of the lever or valve operating 25 means being broken or snapped off, as by accident, the movable valve member will be automatically held in position and preclude leakage of steam.

As materials for the valve parts, phosphor bronze is preferable for the sealing ring on the movable valve member and the bushing, and steel and semi-steel for the remaining parts.

In Fig. 2, the valve member 35 is provided 35 with the cylindrical peripheral portion 36 disposed in advance of the sealing portion 37, for the purpose of affording particular means for locating or positioning the movable valve member when moved to 40 closed position.

It will be understood that other changes and modifications may be made without departing from the invention as defined by the appended claims.

45 We claim.

1. A blow-off cock for boilers, comprising in combination with the boiler casing, of a valve casing communicating directly with the interior of the boiler casing, a movable 50 valve member extending into the interior of the boiler casing and constructed to be moved to closing position under pressure of

the steam contained within the boiler casing, a stem rigidly connected to the movable valve member freely disposed within and 55 extending through the exterior end of said valve casing, said valve casing at its end interior of the boiler casing being frusto-conical and said movable valve member being similarly frusto-conical, said valve casing 60 being provided with a discharge opening located between its said exterior end and its said interior end, said valve casing being substantially free from obstruction between its said interior end and its said discharge 65 opening, a lever for moving said stem and said movable valve member to open position and means for mounting said lever relative to said valve casing and said stem, said mounting means including a pin and slot 70 connection.

2. A blow-off cock for boilers, comprising in combination with the boiler casing, of a valve casing communicating directly with the interior of the boiler casing, a movable 75 valve member extending into the interior of the boiler casing and constructed to be moved to closing position under pressure of the steam contained within the boiler casing, a stem rigidly connected to the movable 80 valve member freely disposed within and extending through the exterior end of said valve casing, said valve casing at its end interior of the boiler casing being frusto-conical and said movable valve member being 85 similarly frusto-conical, said valve casing being provided with a discharge opening located between its said exterior end and its said interior end, said valve casing being substantially free from obstruction between 90 its said interior end and its said discharge opening, a lever for moving said stem and said movable valve member to open position, means for mounting said lever relative to said valve casing and said stem, to provide longitudinal movement of said stem upon rotational movement of said lever, said mounting means including a removable bolt.

In testimony whereof we have signed this 100 specification this 25th day of January, 1917.

PETER B. BIRD.
CHARLES A. BIRD.
